(57) **CLAIM**

The ornamental design for a sectional door panel, as shown and described.

DESCRIPTION

FIG. 1 is a top plan view of a sectional door panel showing my new design;

FIG. 2 is a front elevational view thereof;

FIG. 3 is a right end elevational view thereof, with the left end elevational view being a mirror image thereof;

FIG. 4 is a bottom plan view thereof;

FIG. 5 is a rear elevational view thereof;

FIG. 6 is an enlarged sectional view thereof, taken substantially along the line 6—6 of FIG. 2;

FIG. 7 is a top front and right end enlarged fragmentary perspective view thereof, showing the portion of the design indicated in FIG. 2;

FIG. 8 is a top plan view of a sectional door panel showing a second embodiment of my new design;

FIG. 9 is a front elevational view thereof;

FIG. 10 is a right end elevational view thereof, with the left end elevational view being a mirror image thereof;

FIG. 11 is a bottom plan view thereof;

FIG. 12 is a rear elevational view thereof;

FIG. 13 is an enlarged sectional view thereof, taken substantially along the line 13—13 of FIG. 9; and,

FIG. 14 is a top front and right end enlarged fragmentary perspective view thereof, showing the portion of the design indicated in FIG. 9.

The sectional door panel is shown as discontinuous in the views to indicate indeterminate length.
